[57] CLAIM

The ornamental design for a convertible card table or similar article, substantially as shown and described.

DESCRIPTION

FIG. 1 is a top plan view of a convertible card table or similar article showing my design in position for use as a card table;

FIG. 2 is a side elevational view;

FIG. 3 is an end elevational view;

FIG. 4 is a bottom plan view;

FIG. 5 is a top plan view showing the beverage glass holders in extended position;

FIG. 6 is a view taken in perspective and showing the table in exploded condition for clarity of illustration; and

FIG. 7 is a side elevational view showing the table in converted position for use as a dining table.

The side and end of the table not shown are mirror images of the side and end shown in FIGS. 2 and 3 respectively.

FIG. 1

FIG. 2

FIG. 3

FIG. 4

FIG. 5

FIG. 6

FIG. 7
